RADIATOR FLUSHING UNIT

Filed Nov. 30, 1929

36 Inventor:
Henry A. Lisko
By Leonard S. Kalish
Attorney.

UNITED STATES PATENT OFFICE

HENRY A. LASKO, OF WEST CHESTER, PENNSYLVANIA

RADIATOR-FLUSHING UNIT

Application filed November 30, 1929. Serial No. 410,845.

My invention relates to apparatus adapted for flushing or cleaning out automobile radiators and similar radiators, by continuous flow of water or other cleaning liquid therethrough under pressure, in a direction opposite to the normal direction of flow of liquid through the radiator while the latter is in actual use.

My invention relates more particularly to a novel apparatus or unit, which contains certain facilities in assembled and operative relation to each other, for heating a cleaning liquid, for circulating said liquid under pressure, for straining the cleaning liquid and for mounting a radiator core in operative relation to these facilities or instrumentalities, so that the same may be applied to the radiator with the greatest facility, efficiency and ease.

My invention further relates to novel details of construction which will be described more in detail hereinafter.

With the above ends in view, my invention consists in a unitary piece of apparatus, or what is hereby termed a radiator flushing unit, preferably, though not necessarily, mounted on wheels so as to render it more portable, including a radiator mounting rack or radiator support, upon which the radiator core of an automobile or the like may be mounted, a liquid reservoir for containing the cleaning liquid, suitable heating means associated with the reservoir for heating the cleaning liquid as may be desirable, a liquid pump, preferably of a rotary type, driven by any suitable means, such as an electric motor, said pump having its intake connected to the liquid reservoir and having its discharge port connected to a regulating valve, means for mounting the radiator core upon the radiator rack or support in inverted position, and suitable flexible hose connections for connecting the bottom of the radiator core to the control valve and for connecting the top of the radiator core to the strainer, through which the cleaning liquid is again discharged into the liquid reservoir.

My invention further consists of a novel expandible plug adapted for effecting a quick detachable and liquid pressure proof connec-

tion between the flexible hose and the top or bottom inlet or outlet of the radiator core.

For the purpose of illustrating my invention I have shown in the accompanying drawings one form thereof, which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in which like reference characters indicate like parts.

Figure 1 represents a side elevation of my novel radiator flushing unit, with the liquid reservoir shown in section.

Figure 2 represents a top plan view of the same.

Figure 3 represents a front elevation of the same.

Figure 4 represents a sectional view of an expandible plug embodying my invention.

My novel radiator flushing unit consists of any suitable base 5, of suitable length and width, mounted on suitable wheels or casters 6, so as to permit the unit to be moved or wheeled about with facility. At one end of the base 5 I provide a generally upright panel 7, supported by a pair of suitable braces or stays 8, and having a pair of horizontally projecting supporting brackets 9, upon which the radiator core 10 may be supported, in the inverted position indicated in the drawings. Any suitable clamping means 11 and 12 may be employed for retaining the radiator core 10 in position upon the supports 9. Thus the vertical bracket or rod 12 may be anchored in the up-right panel 7, as by being bolted thereto or otherwise secured thereto, and the clamping rod 11 having a hooked end for engagement with the radiator 10, may be adapted to extend through the bracket 12. By any suitable nut, as for instance, a nut 45, threaded onto the end of the clamping rod 11, the radiator 10 may be secured firmly on the panel 7.

At the opposed end of the base 5, a cylin-

100

drical reservoir 13 is mounted, having its bottom 14 positioned a suitable distance above the base 5, so as to accommodate a gas burner or other heating means 15 beneath the bottom 14 of the reservoir. A suitable lid 16 may be provided on the top of the reservoir 13.

The inlet 17 of the reservoir 13, terminates in a straining or filtering device 18 of any suitable construction within the reservoir 13, so that the liquid returned into the reservoir 13 is strained or filtered before it is actually discharged into the reservoir.

Intermediate of the radiator supporting panel 7 and the reservoir 13, I mount a pump 19 of any suitable type and of appropriate capacity (preferably a rotary pump), with its axis extending transversely of the base 5. An electric motor 20, or any other suitable motor power may be provided on the base 5 in operative juxtaposition to the pump 19, and either directly or otherwise connected to the pump shaft 21.

The outlet 22 of the reservoir 13 is connected to the inlet port 23 of the pump 19, through suitable piping 24. The outlet or discharge port 25 of the pump 19 is connected by the piping 26 to a suitable control valve 27, positioned at a suitable height for convenient manipulation. To the pipe 28 extending from the control valve 27, a flexible hose 29 is attached, the free end of which may then be secured to the bottom outlet 30 of the radiator 10. Suitable piping 31 is attached to the inlet 17 of the reservoir 13, and to the lower end of the piping 31 a flexible hose 32 is attached, the free end of which is in turn connected to the upper inlet 33 of the radiator 10.

In the normal operation of my novel flushing unit, the reservoir 13 is filled with a suitable quantity of water or preferably some suitable cleansing fluid, as indicated in Figure 1. By means of the gas-burner 15 or any other suitable heater, the liquid in the reservoir 13 is heated to a suitable temperature. The radiator 10, mounted upon the panel 7 in the inverted position shown in Figure 1, is then connected to the piping 28 and 31 by the flexible hose connection 29 and 32 respectively. The motor 20 and pump 19 are then set in operation, causing a flow of liquid from the reservoir 13 through the piping 24, through the pump 19 and then out through the piping 26 and control valve 27 into the outlet 30 of the radiator core (normally positioned at the bottom), then through the radiator in a downward direction and through the inlet 33 of the radiator back through the piping 31 into the strainer or filter 18 and then into the reservoir 13. The sediment and other solid matter which is washed out of the radiator by the flow of cleaning liquid is then filtered out by the filter 18 which may be cleaned out or emptied whenever necessary.

The direction of the flow of the cleaning liquid is indicated by the arrows 34.

In Figure 4 I have illustrated an expandable, quick-detachable plug adapted for use on the free ends of the flexible hose 29 and 32, for establishing connection between said hose and the inlet opening 33 and the outlet opening 30 of the radiator core 10. The hose 29 is attached to a nipple 35, of iron or brass or the like, the free end 36 of which is screw-threaded. A manually operable wing nut or the like 37 is threadedly mounted on the threaded portion 36, and immediately adjacent to it a suitable loosely fitting washer 38 is placed over the threaded stem 36. A relatively soft, yieldable and expandable plug 39, formed of rubber or the like, and having a central bore 40 loosely fitting over the threaded portion 36 of the nipple, is provided in abutting relation to the washer 38. A corresponding washer 41 is then placed against the other end of the plug 39, and a suitable nut or other terminal fastening means 42 is then provided to retain the assemblage of the parts on the threaded portion 36 of the nipple 35.

In applying this plug, the nut 37 is loosened up and the plug is then inserted into the opening to which the hose 29 or 32 is to be secured, with the nut 37 remaining outside the opening. The nut 37 is then tightened against the washer 38 and against the body of the plug 39, causing the latter to be squeezed in an axial direction and to expand correspondingly in a radial direction against the inner wall of the opening. By thus tightening the nut 37 the opening is plugged up tight in a quick and convenient manner, which can then be released with equal facility by simply loosening the nut 37 and allowing the plug 39 to contract again.

It will be understood that in the operation of my novel flushing unit the top refill opening 43 of the radiator core 10, as well as the drain pipe usually provided on radiator cores, are suitably plugged up.

By my novel radiator flushing unit, I am enabled to pass water or any other cleaning liquid through the radiator in a direction opposite to the normal flow of water through the radiator when the latter is in use as part of the cooling system of an internal combustion engine. The sediment or scale forming in the radiator while the latter is in use, usually predominates at the top of the radiator where the water enters the radiator core. Thus it is one of the objects of my invention to circulate the cleaning liquid through the radiator in a direction directly opposite to that in which the sediment forming liquid was circulated through the radiator while the latter was in use. By this means the passages of the radiator may be cleaned more quickly, since the obstructions are not only removed by reason of the cleaning liquid but also by

the mechanical action of the stream of fluid. The novel radiator flushing unit of my present invention works equally well on any type of radiator core, whether the same is of the tubular or the cellular or honeycomb type.

5 In extremely clogged up radiator cores it may be necessary to circulate the cleaning liquid through the radiator core comparatively slowly in order to prevent any damage to the core by reason of the pressure of the cleaning liquid. This may be controlled by the valve 27.

10 The cleaning liquid used in this flushing unit may be any suitable aqueous solution or the like, of which many have been devised.

15 I am aware that my invention may be embodied in other specific forms without departing from the spirit or essential attributes thereof, and I therefore desire the present embodiments to be considered in all respects as illustrative and not restrictive, reference being had to the appended claim rather than to the foregoing description to indicate the scope of the invention.

20 Having thus described my invention, what I hereby claim as new and desire to secure by Letters Patent, is:

25 A radiator flushing unit comprising a platform, a liquid reservoir mounted at one end of said platform, an upright radiator support mounted at the opposite end of said platform, including a horizontally extending bracket for receiving the radiator and a clamp for detachably retaining a radiator 30 upon said bracket, a motor driven pump mounted upon said platform having its intake permanently connected with the bottom of said reservoir and having its exhaust adapted for detachable connection with the 35 upper end of a radiator when mounted upon said radiator support, and a pipe communicating with the upper portion of said reservoir and with the lower end of a radiator when mounted upon said radiator support.

40 In testimony whereof, I have hereunto set my hand this 30th day of November, 1929.

HENRY A. LASKO.
